UNITED STATES PATENT OFFICE.

CARROLL ALONZO HOCHWALT, OF DAYTON, OHIO, ASSIGNOR, BY MESNE ASSIGNMENTS, TO GENERAL MOTORS CORPORATION, OF DETROIT, MICHIGAN, A CORPORATION OF DELAWARE.

PROCESS OF PRODUCING DIALKYL SELENIDES AND TELLURIDES.

No Drawing.

Application filed October 3, 1923. Serial No. 666,260.

To all whom it may concern:

Be it known that I, CARROLL ALONZO HOCHWALT, a citizen of the United States of America, residing at Dayton, county of

Montgomery, and State of Ohio, have invented certain new and useful Improvements in Processes of Producing Dialkyl Selenides and Tellurides, of which the following is a full, clear, and exact description.

This invention relates to the manufacture of dialkyl selenides and tellurides, and its principal objects are to improve the yields and reduce the cost of manufacture.

I have found that dialkyl sulphates react directly with metals of the selenium type (selenium and tellurium) yielding the corresponding dialkyl selenides or tellurides.

By way of an example of one method of carrying out my process, I place about 960 grs. of a finely divided sodium selenide (Na_2Se) alloy in a vessel, provided with a reflux condenser, on a water bath, and add 1 liter of diethyl sulphate in portions of 50 to 100 cc. each permitting the reaction, which is exothermic, to subside before adding another portion of the sulphate. After all of the sulphate has been added the mixture is heated by the water bath to about 100° C. for three hours to insure completion of the reaction, water is added to reduce the sodium selenide present, and the diethyl selenide is steam distilled out and collected in another vessel. The reflux apparatus condenses vapours of diethyl sulphate and selenide.

The process may be varied by employing a compound containing other alkyl radicals such as the methyl, propyl, and butyl in place of the ethyl radical and by forming the telluride compound, in place of

the selenide compound and by using potassium in place of sodium. Where these changes are made equi-molecular quantities may be used.

What is claimed is as follows:

1. The process of producing a dialkyl compound of a metal of the selenium type which comprises forming an alkali metal alloy with the said metal, and bringing the alloy into contact with a dialkyl sulphate.

2. A process as defined in claim 1 in which a diethyl sulphate is used and a diethyl compound of the metal is formed.

3. A process as defined in claim 1 in which the metal is selenium and a dialkyl selenide is formed.

4. The process of producing diethyl selenide which comprises forming Na_2Se alloy, and mixing the alloy with diethyl sulphate.

5. The process of producing a dialkyl compound of a metal of the selenium type which comprises forming a finely divided alloy of sodium and the metal, adding a dialkyl sulphate to the alloy, reducing the alloy remaining at the end of this reaction, and steam distilling out the dialkyl compound of the metal.

6. The process of producing a diethyl compound of selenium which comprises forming a finely divided alloy of sodium and the metal, adding diethyl sulphate to the alloy, reducing the alloy, remaining at the end of this reaction, and steam distilling out the diethyl compound of the metal.

In testimony whereof I hereunto affix my signature.

CARROLL ALONZO HOCHWALT.
